(57) **CLAIM**

The ornamental design of a user interface for a franking machine, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a user interface for a franking machine showing our new design; and,

FIG. 2 is a perspective view thereof.

The broken line is the boundary of the claimed design and forms no part thereof.
